VENETIAN BLIND

Clarence W. Morse, Los Angeles, Calif.

Application November 18, 1940, Serial No. 366,037

18 Claims. (Cl. 156—17)

My invention relates to a Venetian blind, and more particularly to a Venetian blind having the usual rout openings through which cord or other supporting means extends, for the support of the bottom member of the blind.

The principal object of the invention is to provide such a Venetian blind that may be closed, despite the supporting cord means, to a point where the spaces between the slats are substantially closed, thus substantially preventing the penetration of light.

Heretofore, in blinds of this character, the supporting cord means has prevented the slats from coming together sufficiently close to shut out light; in fact, the cord means holds the slats apart, preventing closure of the blind.

In Venetian blinds now in use, it is difficult, if not impossible, to raise and lower the blinds when the slats are in their closed position. It is an object of my invention to provide means whereby the blind may be raised or lowered even though the slats are in their closed position.

Still another object of the invention is to provide means whereby short, standard lengths of Venetian blind slats may be used, irrespective of the over-all length desired for a window.

Other objects of the present invention are to provide such a blind that is positive in operation, easily installed, economical of manufacture, and relatively simple.

The invention also comprises novel details of construction and novel combinations and arrangements of parts, which will more fully appear in the course of the following description. However, the drawings merely show and the following description merely describes embodiments of the present invention, which are given by way of illustration or example only.

In the drawings, like reference characters designate similar parts in the several views.

Fig. 1 is a broken, perspective view of a Venetian blind carrying out the foregoing objects.

Fig. 2 is an enlarged transverse section taken on the line 2—2 of Fig. 1, but showing the blind in a closed position.

Fig. 3 is a broken elevation taken on the line 3—3 of Fig. 2.

Fig. 4 is a transverse section taken on the line 4—4 of Fig. 3.

Fig. 5 is a broken side elevation looking in the direction of the arrow A of Fig. 1, but showing the blind in a closed position.

Fig. 6 is a section taken on the line 6—6 of Fig. 3.

Fig. 7 is a broken elevation of a modified embodiment, taken on the line 7—7 of Fig. 8.

Fig. 8 is a vertical section taken on the line 8—8 of Fig. 7.

Fig. 9 is a side elevation looking in the direction of the arrow 9 of Fig. 7.

Fig. 10 is a broken elevation of a still further modified construction.

Fig. 11 is a section taken on the line 11—11 of Fig. 10.

Fig. 12 is a perspective view of a connecting member comprised in the latter embodiment.

Referring more in detail to the drawings, the reference numeral 6 generally designates the foot block of a Venetian blind, which is supported by means of cords 7 and 8. Rear and front straps 9 and 10, respectively, are fastened to the lower side of the block 6 by suitable tack means 12. The straps 9 and 10 and the cords 7 and 8 are supported from the head (not shown) of the Venetian blind. The head of course includes any conventional adjusting means for the straps and cords.

Sewed to the opposing faces of the straps 9 and 10 are cross tapes 13, which support Venetian blind slats 14, the slats 14 having elongated rout openings 15 therein for the cords 7 and 8.

The slats 14 are preferably resilient metal that is adapted to be coiled upon itself and when released to resume the shape shown in Fig. 1. Alined with the ends of the rout openings 15, the slats 14 have beads 16 and 17 bent in opposite directions with regard to each face of the slats. The slats have similar beads, in order that they may provide complementary grooves for the cords when the slats are moved to a closed position.

In the modified construction shown in Figs. 7 to 9, similar straps 9 and 10 and cross tapes 13 are utilized. The slats 20, however, are preferably substantially S shape in cross section and in end elevation, as best shown in Fig. 9. Grooves 21 and 22 are likewise arranged at opposite sides of a rout opening 23 for the cord 7. The grooves 21 and 22 form bosses on the backs of the curves of the S shape of each slat. The grooves 21 and 22 are complementary, in order to receive the cord 7 therebetween.

In the modified construction shown in the Figs. 10 to 12, sections 24 and 25 of a Venetian blind slat are shown as being held in alignment by a connecting member 26, which comprises a face plate 27 provided with a rout opening 28 for receiving the cord 7. Ribs 29 and 30, at opposite sides of the rout opening 28, project in opposite

directions with respect to the cord 1 and provide inclined grooves for engaging the cord. The grooves 29 and 30 are inclined sufficiently to permit the slats to overlap at an angle, as shown in Fig. 11, while the cord 1 remains vertical.

The face plate 27 has flanges 31 and 32 bent downwardly and upwardly toward each other. The flanges 31 and 32 form gripping fingers for the Venetian slat sections 24 and 25. These Venetian slat sections may be of either wood or metal. Moreover, the ribs 29 and 30 provide abutments for the ends of the slat sections 24 and 25.

In the use of my invention, it is believed clear that all forms of the blind are operated in the usual manner of Venetian blinds. The angular arrangement of the slats and foot block 6 is adjusted by means of the tapes 9 and 10. Moreover, the blind may be raised by drawing upward the cords 7 and 8.

When the blind is moved to a closed position, by moving the tapes 9 downward, as indicated by the arrow B, and by moving the tapes 10 upward, as indicated by the arrow C, the slats are moved to a position in which they touch each other. In this position the only light that will pass through will be through the complementary grooves 16 and 17, which is slight, if any. Otherwise, the slats will substantially close out light between the slats. When the blind is moved to the closed position, by moving the straps in the directions of the arrows B and C, the raised portions of the beads in each of the forms will project outwardly. This permits a very close association of the edge of one slat with the side of the next slat without interference by the supporting cord.

The blind shown in Figs. 2 and 5 is moved to its open position by moving the straps 9 and 10 in the directions of the arrows D and E. The blind shown in Figs. 8 and 9 is moved to its open position by moving the straps 9 and 10 in the directions of the arrows F and G.

In the use of the form shown in Figs. 10 to 12, the slat sections are slid longitudinally under the gripping fingers 31 and 32 until their ends substantially abut the ribs 29 and 30. It is believed clear that the ribs 29 and 30 on adjacent slat connecting members will form complementary grooves for receiving the cord 1, so that the slats may overlap and still the supporting cords will not keep the slats apart.

It is believed clear that the slot sections 24 and 25 may be of short, standard lengths, but that such sections may be connected together to obtain any desired over-all length. The cost of short, standard sections is considerably less than the same amount of board feet in long slats. This applies particularly to wooden Venetian blind slats.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications which may fall within the scope of the appended claims.

Having thus described my invention, what I claim and desire to secure by Letters Patent is:

1. A Venetian blind comprising a plurality of slats having substantially aligned apertures, supporting cord means arranged in the apertures,

the slots having means offset beyond the faces, forming transverse grooves between the apertures and the sides of the slats, and the grooves on adjacent slats being complementary to each other for receiving the cord means, when the blind is moved to a closed position.

2. A Venetian blind comprising a plurality of slats having substantially aligned apertures, supporting cord means arranged in the apertures, the slats having means offset beyond the faces thereof, forming grooves facing in opposite directions at opposite sides of the apertures, and the grooves being disposed to receive the cord means, when the blind is moved to a closed position.

3. A Venetian blind comprising a plurality of slats having substantially aligned apertures, supporting cord means arranged in the apertures, straps having cross tapes disposed to support and adjust the position of the slats, the slats having means offset beyond a face thereof, forming grooves between the apertures and a side of the slats, the cross tapes being offset with respect to the grooves, and the grooves being disposed to receive the cord means, when the blind is moved to a closed position.

4. A Venetian blind comprising a plurality of slats having substantially aligned apertures, supporting cord means arranged in the apertures, the slats having means offset beyond a face thereof, forming grooves between the apertures and a side of the slats and the grooves being disposed to receive the cord means, when the blind is moved to a closed position.

5. A Venetian blind slat comprising an elongated body member having at least one aperture for receiving a supporting cord, the slat having means offset beyond a face thereof, forming a transverse groove between the aperture and the side of the slat disposed to receive the cord in one position of the slat, the groove having an interior cross sectional shape similar to the contour of the cord.

6. A Venetian blind slat comprising an elongated body member having at least one aperture for receiving a supporting cord, the slat having means offset beyond the faces thereof, forming transverse grooves in opposite directions at opposite sides of the aperture, to receive the cord in one position of the slat.

7. A metal Venetian blind slat comprising an elongated body member having at least one aperture for receiving a supporting cord, the slat being gradually curved and having means offset beyond the faces thereof, forming transverse grooves in opposite directions at opposite sides of the aperture, to receive the cord in one position of the slat.

8. A metal Venetian blind slat comprising an elongated body member having at least one aperture for receiving a supporting cord, the slat having a single convex-concave curve from edge to edge, the curve being about a single center, and the slat having means offset beyond the faces thereof, forming transverse grooves in opposite directions at opposite sides of the aperture, to receive the cord in one position of the slat, the groove on one side of the aperture extending in the direction of the curve of the body of the slat and the groove on the opposite side of the aperture extending in the opposite direction to that of the curve of the body of the slat.

9. A metal Venetian blind slat comprising a body member apertured to receive supporting cord means, the slat being curved from edge to

edge in substantially an S shape in cross section, the slat having bosses at opposite sides of its aperture, on the outer faces of the curves of the S, providing grooves on the inner faces of the S for receiving the supporting cord means.

10. A Venetian blind comprising a plurality of metal slats each being apertured, supporting cord means in the apertures of the slats, the slats being curved from edge to edge in substantially an S shape in cross section, the slats having bosses at opposite sides of their apertures, on the outer faces of the curves of the S, bosses of adjacent slats, providing facing, complementary grooves on the inner faces of the curves of adjacent slats, for receiving the supporting cord means.

11. A metal Venetian blind slat comprising a body member apertured to receive supporting cord means, the slat being cross sectionally curved and having means offset beyond a face thereof, forming a groove on the inside of the curve and at a side of the aperture, for receiving the supporting cord means.

12. A metal Venetian blind slat comprising a body member apertured to receive supporting cord means, the slat being cross sectionally curved and having means offset beyond a face thereof, forming a groove on the outside of the curve and at a side of the aperture, for receiving the supporting cord means.

13. A metal Venetian blind slat comprising a body member apertured to receive supporting cord means, the slat being cross sectionally curved, and having means offset beyond the faces thereof, forming alined grooves on the curved slat at opposite sides of the aperture, for receiving the supporting cord means.

14. A metal Venetian blind slat comprising a body member apertured to receive supporting cord means, the slat being cross sectionally

curved in substantially an S shape, and having means offset beyond the faces thereof, forming alined grooves on the curves of the slat at opposite sides of the aperture, for receiving the supporting cord means.

15. A Venetian blind slat comprising connecting means having an aperture and having a boss providing a groove at a side of the aperture for receiving supporting cord means, and slat sections having sliding connections with the connecting means, the boss providing inward sliding limits for the slat sections with respect to connecting means.

16. A Venetian blind slat comprising connecting means having an aperture and having bosses providing alined grooves at opposite sides of the aperture, for receiving supporting cord means, and slat sections having sliding connections with the connecting means, the bosses providing inward sliding limits for the slat sections with respect to connecting means.

17. A Venetian blind slat comprising apertured connecting means having a boss providing a groove at a side of the aperture and having gripping means thereon, and slat sections projecting from the connecting means in opposite directions and gripped by said gripping means, the boss providing inward sliding limits for the slat sections with respect to connecting means.

18. A Venetian blind slat comprising apertured connecting means having a boss providing a groove at a side of the aperture and having clamping fingers projecting toward each other, and slat sections projecting from the connecting means in opposite directions and clamped by said clamping fingers, the boss providing inward sliding limits for the slat sections with respect to the connecting means.

CLARENCE W. MORSE.
